UNITED STATES PATENT OFFICE.

ARTHUR B. HARRISON, OF BALTIMORE, MARYLAND, ASSIGNOR OF THREE-FOURTHS TO DUNCAN VEASEY, OF SAME PLACE, AND WILLIAM M. HARRISON, OF LAUREL, MARYLAND.

HAND CHEMICAL FIRE-EXTINGUISHER.

SPECIFICATION forming part of Letters Patent No. 329,309, dated October 27, 1885.

Application filed May 11, 1885. Serial No. 165,156. (No model.)

To all whom it may concern:

Be it known that I, ARTHUR B. HARRISON, of the city of Baltimore and State of Maryland, have invented certain new and useful Improvements in Chemical Fire-Extinguishers, of which the following is a specification, reference being had to the accompanying drawings, forming part hereof, in which—

Figure 1 is a view, partly in section and partly in side elevation, showing my invention. Fig. 2 is a detail side elevation of my improved plug, and Fig. 3 is a view of a modified form of piston rod or handle.

Like letters mark the same parts in all the figures.

My invention relates to devices for storing and applying chemicals for extinguishing fires; and it consists in a syringe for that purpose, the construction, arrangement, and combination of the parts of which I shall now proceed to fully describe, the specific points of novelty being set forth in the claims appended to this specification.

Referring to the drawings by letter, A is the body of a syringe, or cylinder thereof, which is of ordinary construction, being provided with a removable cover or lid, a, at one end and a contracted cone-shaped point, a', at the other, said point terminating in an opening of the desired size to serve as an exit or discharge orifice, and which, when the device is stored and not in use, is stopped up with a plug, B, (illustrated detached from the syringe on Fig. 2,) formed of a stem, b, and head b', the stem being inserted in the exit and soldered therein, as shown in Fig. 1. The lid a is centrally perforated to admit of the passage of a piston rod or handle, C, by which the piston D within the cylinder is operated. The piston D is composed of a leather or other flexible washer, d, between two sheet-metal washers, d' and d'', each of which is dish-shaped, the washer d' being of a greater diameter than the washer d'', and having its dish or concavity in the opposite direction thereto. These washers are pressed together upon the flexible washer by means of a screw, d', which passes through all three of the

washers or disks and engages with its thread a nut, d''. It is, however, not of sufficient length to pass through said nut, but when screwed home reaches only about the middle of it, as seen in Fig. 1. A disk, d'', of paste-board or card-board, lies next to the sheet-metal washer d', between it and the nut d'', and a small disk or washer, d'', of rubber is glued on the inner side of the lid a and forms a packing for the piston-rod. The tip or plug being soldered in and the cylinder being filled with fluid, the piston is inserted, and the space between the card-board being filled with wax the apparatus is hermetically sealed and none of the fluid can escape.

When it is desired to use the device, the handle is inserted through the lid and screwed into the nut d'' and the plug knocked out, when by pressing in the piston-rod the fluid will be ejected with great force.

The construction shown in Fig. 3 differs only in the construction of the handle, which extends through the piston and has a nut on its inner end, being non-detachable.

My device possesses many advantages over any of the hand devices in use for extinguishing fires. The fluid can be forced to places inaccessible to that from a broken hand-grenade, and can be thrown upon goods—such as dry-goods—which would not break a grenade. It is thoroughly air-tight and will preserve the fluid and prevent waste thereof. When a small quantity only is necessary, it can be applied, the operator being able to stop the stream at any time. It is cheap, durable, and simple, and when not in use occupies a space but slightly larger than the cylinder, the handle being removable, as before described. It is so constructed that no liquid can be drawn into the cylinder by a backward movement of the piston, the leather (or flexible) washer being bent forward in dish form by the pressure of the tin or sheet-metal washers or disks, and being thus rendered operative in a forward movement only. A backward movement will cause all fluid in the rear of the piston to pass around it and be expelled by the next forward movement.

Having thus fully described my invention, what I claim, and desire to secure by Letters Patent of the United States, is—

1. A chemical fire-extinguisher consisting of a cylinder having a sealed exit, an interior piston, a sealed rear end, and a removable piston rod or handle, as set forth.
2. In combination, the piston-rod, the flexi-

ble disk, the two oppositely-concaved metal disks of different diameters, the screw and nut, the card-board disk, and the wax seal, as set forth.

ARTHUR B. HARRISON.

FRANK T. HARRISON.

Correction in Letters Patent No. 329,309.

It is hereby certified that the name of one of the assignees in Letters Patent No. 329,309, granted October 27, 1885, upon the application of Arthur B. Harrison, of Baltimore, Maryland, for an improvement in "Hand Chemical Fire-Extinguishers," was erroneously written and printed "Duncan Veasey" instead of *Duncan Veazey*; and that the said Letters Patent should be read with this correction therein that the same may conform to the record of the case in the Patent Office.

Signed, countersigned, and sealed this 3d day of November, A. D. 1885.

[SEAL.]

H. L. MULDROW,
Acting Secretary of the Interior.

Countersigned:

M. V. MONTGOMERY,
Commissioner of Patents.
